UNITED STATES PATENT OFFICE.

WALTER GARTNER, OF HAMBURG, GERMANY.

FURNACE.

1,089,409.

Specification of Letters Patent. Patented Mar. 10, 1914.

Application filed July 19, 1913. Serial No. 779,966.

To all whom it may concern:

Be it known that I, WALTER GARTNER, subject of the Emperor of Germany, residing at Ferdinandstrasse 25, Hamburg, in Germany, have invented a certain new and useful Furnace, of which the following is a specification.

This invention relates to a furnace, especially suitable for steam generators, of the type in which the fuel is fed laterally to the fire grate through inclined passages in which the fuel is partially coked before reaching the grate, fireproof partitions, with or without air passages, restricting the size of the fuel passages.

The object of this invention, which is more particularly applicable to water-tube steam generators, is to provide a furnace in which the combustion of the fuel on the grate can be more readily controlled than in those of the type above described hitherto made.

According to this invention supplementary side grates are formed along either side of the main grate so as to occupy a position between the latter and the fuel passages. Air, which is warmed in the roof of the furnace chamber, is supplied to the side grates through conduits provided with dampers enabling the amount of air delivered through the side grates to be varied independently of the amount of air which passes through the main grate from the ashpit. Further, the temperature of the air below the side grates can be varied independently of that supplied to the main grate and in this way a smokeless fire is insured and combustion can be accelerated or retarded by varying the supply of air to the side grates or main grate. As in previous constructions passages for cooling air are preferably formed in the fireproof partitions which limit the upper sides of the fuel passages, the air being drawn direct from the atmosphere. After cooling the rear wall of the fireproof partition, to prevent the coal in contact therewith being prematurely coked, the cooling air flows through suitable apertures or conduits to the combustion chamber where it assists combustion after being heated by flowing through the fireproof partition. In this way not only is warm air supplied to the combustion chamber to support combustion but further a continuous circulation of cold air through the cooling conduits is insured.

In the accompanying drawings which show a furnace for a water-tube steam generator in accordance with this invention, Figure 1 is a sectional side elevation through the grate and furnace chamber on the line 1—1 of Fig. 3. Fig. 2 is a cross-section through the furnace chamber and the furnace, and Fig. 3 shows the furnace partly in end elevation and partly in section through the conduits which supply air to the main and supplementary side grates.

In the construction illustrated the furnace comprises a combustion chamber A provided with a curved grate B to which fuel is supplied through inclined lateral passages C, and hoppers C' of any suitable type communicating with these passages. As in previous constructions, fireproof partitions D are provided which form the walls of the combustion chamber, and the undersides of these partitions limit the inclined passages through which the fuel is fed to the grate. According to this invention on either side of the main grate, and separate therefrom in so far as the air supply is concerned, are supplementary side grates E, these grates occupying a position intermediate between the lateral edges of the main grate and the fuel passages C.

The roof of the furnace chamber is formed hollow and communicates with the atmosphere, air chambers F being thus provided above the combustion chamber. The air to support combustion enters the chambers F at the rear, open end thereof (Fig. 1) and passes downward through vertical conduits F' to the horizontal conduits E' arranged below each of the supplementary side grates E. In this way warm air is supplied to the supplementary grates and a damper F² in the conduit F' enables the amount of air supplied to be varied. Further, additional cold air from the atmosphere can be introduced into the conduits E' by means of suitable dampers or doors E² formed on the front wall of the furnace.

As already stated, the air supplied to the main grate B is independent of that which flows through the conduits E' to the supplementary grates E. Cold air is introduced to the main grate through a door or damper B' which closes the ashpit and additional warm air can be supplied to the main grate through branch passages G controlled by dampers G', these passages communicating with the passages F' which supply the hot

air to the conduits E'. Thus hot air can be supplied to the main and supplementary grates simultaneously or to the main or side grates only, while if desired, the air can be 5 shut off from the side grates entirely, in which case these merely constitute extensions of the fuel passages, the size of the fire-grate being thereby materially reduced.

The fireproof partitions D are provided 10 at their rear portions with air chambers D' communicating directly with the atmosphere by means of suitable doors or dampers D''. The air after flowing through the cooling chambers D' to prevent the fuel in the fuel 15 passages becoming prematurely coked, passes through inclined conduits D''' to the combustion chamber, where, being now warm, it assists to support combustion and further insures free further circulation of 20 cold air through the cooling chambers D'.

Although above described with reference to a steam generator of the water-tube type, it will be appreciated that, suitably modified, the invention is capable of being applied to other forms of generator and to all 25 furnaces of the laterally fed type irrespective of the purpose to which such furnaces are put.

What I claim as my invention and desire 30 to secure by Letters Patent is:—

1. In a furnace, the combination of a combustion chamber, a main fire grate, a fuel passage leading thereto on either side thereof, a supplementary grate on either side of 35 the main grate, means for supplying air to the under side of the main grate, separate passages adapted to supply warm air to each supplementary side grate, air supply conduits in the walls of the combustion chamber 40 leading to the under side of the main grate and to the air passages below the supplementary grates and means for controlling the air supplied through said conduits to the supplementary grates independently of that 45 supplied to the main grate.

2. In a furnace the combination of a combustion chamber, a main fire-grate, a fuel passage leading thereto on either side thereof, a supplementary grate on either side of 50 the main grate, means for supplying air to the underside of the main grate, separate passages adapted to supply warm air to each

supplementary side grate, air supply conduits in the walls of the combustion chamber leading to the underside of the main grate 55 and to the air passages below the supplementary grates and means for controlling the air supplied to the main and supplementary grates.

3. In a furnace the combination of a combustion chamber, a main fire-grate, a fuel passage leading thereto on either side thereof, a supplementary grate on either side of the main grate, an air passage below each supplementary grate communicating with the atmosphere, means for controlling the amount of cold air admitted to said conduits, air supply conduits formed in the walls of the combustion chamber communicating with the conduits below each supplementary grate and also leading to the underside of the main grate and means for controlling the amount of hot air supplied to the main and supplementary grates. 60

4. In a furnace for steam generators the 75 combination of a combustion chamber, a main fire-grate, a fuel passage leading thereto on either side thereof, a refractory partition above each fuel passage, a cooling chamber in each partition communicating 80 directly with the atmosphere, means for controlling the amount of cold air admitted to said cooling chambers, passages connecting said cooling chambers with the combustion chamber, a supplementary grate on either side of 85 the main grate, an air passage below each supplementary grate communicating with the atmosphere, means for controlling the amount of cold air admitted to said conduits, air supply conduits formed in the 90 walls of the combustion chamber communicating with the conduits below each supplementary grate and also leading to the underside of the main grate and means for controlling the amount of hot air supplied to 95 the main and supplementary grates.

In testimony whereof I have signed my name to this specification in the presence of two subscribing witnesses.

WALTER GARTNER.
